Primary Examiner — Paula Allen Greene(74) *Attorney, Agent, or Firm* — ScienBiziP, P.C.(57) **CLAIM**

The ornamental design for an earphone, as shown and described.

DESCRIPTION

FIG. 1 is a first perspective view of an earphone showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view showing the earphone in a use state.

The broken lines in FIG. 9 depicting a cable and another earphone form no part of the claimed design.

The broken lines depict environment that forms no part of the claimed design.

1 Claim, 9 Drawing Sheets(56)
